NAIL FEEDING DEVICE

Gerald C. Paxton, Sanger, Calif., assignor to General Nailing Machine Corporation, Sanger, Calif., a corporation of California

Application December 9, 1947, Serial No. 790,577

14 Claims. (Cl. 1—16)

1

This invention relates generally to improvements in box nailing machines, and in particular the invention has for an object the provision of a novel nail feeding device or pick mechanism.

In box nailing machines it is conventional to employ a nail feeding device between the nail runs of a shaker type, nail feed hopper and the feed tubes leading to the nailing unit chucks.

The present invention presents a novel device for the purpose; such device being arranged in a manner to reduce the number of nail runs required. Each nail pick which the device includes is operative to pick up, transfer, and discharge to corresponding feed tubes a pair of nails with each oscillation of said pick.

A further object of the invention is to provide a nail feeding device, as above, wherein the same is selectively adjustable so that with one oscillation of each pick, the same will feed either one or two nails. The picks and the actuating mechanism therefor are of novel construction for this purpose.

An additional object is to yieldably mount the picks, which are of rotary type, so that structural damage is avoided, should a nail jam in the mechanism.

A further object of the invention is to provide a practical nail feeding device, and one which will be exceedingly effective for the purpose for which it is designed.

These objects are accomplished by means of such structure and relative arrangement of parts as will fully appear by a perusal of the following specification and claims.

In the drawings:

Fig. 1 is a top plan view of the improved nail feeding device, with the rotary nail picks in starting position.

Fig. 2 is a similar view, but shows the rotary nail picks as cam actuated to one feeding or nail discharging position.

Fig. 3 is a sectional elevation showing one of the rotary nail picks and the actuating mechanism therefor.

Fig. 4 is a fragmentary plan view showing the arrangement of the actuating mechanism for single nail delivery.

Fig. 5 is a fragmentary elevation of the motion translating mechanism employed in connection with the actuating shaft.

Referring now more particularly to the characters of reference on the drawings, the nail feeding device is adapted to be interposed, in a box nailing machine, between a shaker-type nail feed hopper and the nailing units of the machine;

2

such hopper being of the type which includes a fixed, forwardly and downwardly inclined nail chute 1 which has a plurality of transversely spaced nail slots or runs 2, into which the nails are fed in rows 3 from the hopper. Each nail run 2 is defined by a pair of adjacent but spaced parallel plates 4.

The plates 4 terminate, at their lower ends, adjacent but short of a rigidly mounted horizontal cross bar 5.

In association with the bottom of the horizontal cross bar 5, and the adjacent end of the nail chute 1, there is a member 6 which forms a pair of downwardly extending nail feed passages 7 corresponding to, but disposed on opposite sides of, each nail run 2, directly between the lower end of chute 1 and the adjacent face of cross bar 5. Each nail feed passage 7 is connected to a duct (not shown), which in turn delivers to a corresponding one of the nailing chucks of the machine.

In direct alinement with each nail run 2, the device includes a rotary pick, indicated generally at 8, and as the construction and operation of each of the rotary picks 8 is identical, a description of one will suffice for all.

Each rotary pick comprises a horizontally disposed rotary body 9 which seats atop the horizontal cross bar 5, and is turnable about a vertical stem 10 secured to said cross bar by a headed screw 11, whose head is disposed some distance above the body 9. A combination torsion and compression spring 12 of helical type extends about the vertical stem 10 between the body 9 and the head of screw 11. One end of such spring is anchored to the body 9 as shown, while the other end of said spring is anchored to an upstanding stop pin 13 on the cross bar 5 laterally in one direction of the body 9.

The body 9 is formed, on the side adjacent the corresponding nail run 2 and plates 4, with a radially projecting segmental carrier 14 whose outer arcuate edge runs in close symmetrical relation to arcuate ends of said corresponding plates 4, as at 15.

The segmental carrier 14 is formed with a pair of circumferentially spaced nail receiving notches 16 adapted to register alternately with the corresponding nail run 2 upon oscillation of the pick. On opposite sides of each nail run 2, the corresponding plates 4 are formed, at their lower end portions, with nail passage slots 17; the plates being slopingly recessed, as at 18, rearwardly of the corresponding slots 17. The slots 17 register with corresponding passages 7.

Additionally, the upper or working face of the carrier 14 is inclined outwardly and downwardly, as at 19.

The springs 12 normally maintain each pick 8 with one of the nail receiving notches 16 of the corresponding carrier 14 in alignment with the adjacent nail run 2, whereby a nail from the row 3 feeds to such notch. This one notch 16 is the one opposite the corresponding stop 13. With rotary oscillation of each pick in a direction such that the carrier moves only through a part-cycle first in a direction away from the corresponding stop 13 and then back to engagement therewith, a nail is picked from the nail run 2 by each notch 16 and is transferred, along ends 15, to and discharged through the corresponding nail passage slot 17. As each nail receiving notch 16, with the nail therein, registers with the corresponding nail passage slot 17, the nail head slides from the inclined face 19 through said slot; the nail then dropping into the corresponding nail feed passage 7.

The rotary nail picks 8 are actuated, to accomplish the above two-nail delivery with each oscillation, by means of the following mechanism:

Across shaft 20 is journaled directly ahead of the cross bar 5, and the nail picks 8 each include a cam arm 21 projecting therefrom on the side opposite the carrier 14 and in overhanging relation and at a tangent to the upper periphery of said shaft.

A plurality of actuating buttons 22 are removably secured to the cross shaft 20 in spaced circumferential relation; there being a circumferential row of such buttons for each cam arm 21. The shaft 20 is adapted to be driven counter-clockwise in a manner to be later described and the cam surfaces 21a of the cam arms 21 extend across the path of travel of the buttons 22 with the rotation of such shaft and face contra to the direction of travel of such buttons. Thus, since the cam arms overhang the periphery of the shaft 20 at a tangent thereto, as the shaft 20 rotates, it carries the buttons 22 first into engagement with the lower edges of the cam surfaces and at an angle thereto and then along said surfaces. Thus, as each button engages a cam arm in this fashion it moves the corresponding pick through one stroke of its oscillation and which is in opposition to the torsion of the spring 12. After swinging the arm 21 to impart such initial stroke to the corresponding pick 8, the button escapes such arm, whereupon the torsion spring 12 reacts to rotate the pick through the return stroke back into engagement with the adjacent stop 13.

It will thus be noted that with rotation of the cross shaft 20 in the direction indicated by the arrow in Fig. 3, the picks are recurrently reciprocated; the number of reciprocations of each pick 8 corresponding to the number of buttons 22 in each circumferential row. In the present embodiment there are three of such buttons in each row so that with each revolution of the cross shaft 20 the corresponding picks 8 oscillate a like number of times, i. e. three oscillations with the delivery of six nails.

The cross shaft 20 is intermittently turned through a part circle, here a one-third turn, by means of a Geneva movement, indicated generally at 23, which movement is interposed between a shaft 20a and the shaft 20. The shaft 20a is rocked back and forth by a radial lever 24 operated by a power oscillated rod 25. This Geneva movement is arranged to cause a dwell at

the reversing point of the picks so that there is sufficient time lag for a nail to feed from each nail run 2 into the then registering notch 16. At the starting point there is of course sufficient lag between the spring return of picks and re-engagement of the buttons with the cam arms to permit the picks to each receive a nail from the corresponding nail run.

The vertical stem 10 corresponding to each rotary pick 8 is tapered downwardly at the portion which forms the bearing for the body 9 of the pick; such downward taper being indicated at 26. The reason for this taper is that it permits the corresponding pick body 9 to cant upward, as shown by the dotted lines in Fig. 3 should a nail jam between the carrier 14 and one of the plates 4. This canting is effected by the upper pressure of the button crossing diagonally against the lower edge of the cam surface 21a on the cam arm 21 which at that time overcomes the compression strength of the spring 12. When the body 9 and related cam arm 21 tilts upwardly, an engaged button 22 may escape the lower edge of the cam surface and travel along beneath the arm without causing structural damage, as would otherwise occur. Additionally, the above tilting of the body 9 tends to facilitate clearing of a jammed nail.

As the springs 12 are also compression springs, they normally maintain the rotary picks 8 seated level on the cross bar 5, and also return said picks to such position after tilting on account of a nail jam.

Under certain working conditions it may be desirable to accomplish single nail delivery by each carrier upon oscillation thereof through its cycle.

This is accomplished by the simple expedient of substituting for the large actuated buttons 22 smaller actuating buttons, such as is shown at 27 in Fig. 4. The result is an initial stroke of each carrier 14 a distance sufficient that one nail receiving notch 16 transfers a nail from the nail run 2 to one of the nail passage slots 17, as at A in Fig. 4, yet without said carrier moving far enough for the other nail receiving notch to pick a nail from said run, as at B in said figure. To accomplish this, it is necessary that the spacing between the nail receiving notches 16 be sufficiently great so that said one notch 16 can make discharging register with the corresponding nail passage slot 17 before the other notch 16 registers with the nail run 2.

The above described nail feeding device, while simple, practical, and reliable in its construction and operation, provides for the feeding of nails either in dual or single delivery from each nail run 2, selectively.

Additionally, the mounting of the rotary picks 8, is such that a nail jam can occur without structural damage to the device; the resilient or tiltable mounting of the picks being a safety measure.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the fol-

lowing is claimed as new and useful, and upon which Letters Patent are desired:

1. A nail feeding device comprising, with an inclined chute having a nail run therein open at its lower end, a supporting member mounted adjacent the lower end of the nail run, an oscillatory pick mounted on the supporting member in cooperating relation to the lower end of the chute and said nail run, the pick having a pair of spaced nail receiving notches therein adapted to register one at a time with the nail run whereby to receive a single nail therefrom, there being nail passage slots in the chute open to its lower end on opposite sides of the nail run, means forming a nail feed duct below each such slot, and means to oscillate the pick to alternately register the nail receiving notches with said nail run and corresponding nail passage slots.

2. A nail feeding device comprising, with an inclined chute having a nail run therein open at its lower end, a supporting member mounted adjacent the lower end of the nail run, an oscillatory pick mounted on the supporting member in cooperating relation to the lower end of the chute and said nail run, the pick having a pair of spaced nail receiving notches therein adapted to register one at a time with the nail run whereby to receive a single nail therefrom, there being nail passage slots in the chute open to its lower end on opposite sides of the nail run, means forming a nail feed duct below each such slot, and means to oscillate the pick to alternately register the nail receiving notches with said nail run and corresponding nail passage slots; the pick being mounted for oscillation about an upstanding axis and having a working edge running in close symmetrical relation to the lower end of the chute.

3. A nail feeding device comprising, with an inclined chute having a nail run therein open at its lower end, a supporting member mounted adjacent the lower end of the nail run, an oscillatory pick mounted on the supporting member in cooperating relation to the lower end of the chute and said nail run, the pick having a pair of spaced nail receiving notches therein adapted to register one at a time with the nail run whereby to receive a single nail therefrom, there being nail passage slots in the chute open to its lower end on opposite sides of the nail run, means forming a nail feed duct below each such slot, and means to oscillate the pick to alternately register the nail receiving notches with said nail run and corresponding nail passage slots; the pick being mounted for oscillation about an upstanding axis, and said last named means including a power actuated mechanism operative to intermittently impart part-circle rotation to the pick in one direction, and a spring acting in alternate relation to said mechanism to impart return part-circle rotation to the pick in the opposite direction.

4. A nail feeding device comprising, with an inclined chute having a nail run therein open at its lower end, a supporting member mounted adjacent the lower end of the nail run, a pick mounted on the supporting member in cooperating relation to the lower end of the chute and said nail run, the pick having a pair of spaced nail receiving notches therein adapted to register one at a time with the nail run whereby to receive a single nail therefrom, there being nail passage slots in the chute open to its lower end on opposite sides of the nail run, means forming a nail feed duct below each such slot, a vertical stem on

the member, the pick being turnable about said stem, means to oscillate the pick about the stem to alternately register the nail receiving notches with said nail run and a corresponding nail passage slot, the pick being so mounted on the stem as to allow relative vertical tilting of the pick.

5. A nail feeding device comprising, with an inclined chute having a nail run therein open at its lower end, a supporting member mounted adjacent the lower end of the nail run, an oscillatory pick mounted on the supporting member in cooperating relation to the lower end of the chute and said nail run, the pick having a pair of spaced nail receiving notches therein adapted to register one at a time with the nail run whereby to receive a single nail therefrom, there being nail passage slots in the chute open to its lower end on opposite sides of the nail run, means forming a nail feed duct below each such slot, and means to oscillate the pick to alternately register the nail receiving notches with said nail run and corresponding nail passage slots; the pick including a cam thereon, and said last named means including a rotary shaft having an element thereon adapted to recurringly engage and move said cam through a predetermined path.

6. A nail feeding device comprising, with an inclined chute having a nail run therein open at its lower end, a supporting member mounted adjacent the lower end of the nail run, a rotary pick journaled on the member for oscillation about an upstanding axis, symmetrical and cooperative working edges on the pick and chute, the pick having a pair of spaced nail receiving notches in its working edge and the chute having a corresponding pair of nail passage slots therein open to the working edge on opposite sides of the nail run, the notches being adapted upon oscillation of the pick to alternately register with the nail run and to receive a nail therefrom, and to then transfer said nail to and discharge the same through the corresponding nail passage slot, and means to oscillate the pick.

7. A nail feeding device comprising, with an inclined chute having a nail run therein open at its lower end, a supporting member mounted adjacent the lower end of the nail run, a rotary pick journaled on the member for oscillation about an upstanding axis, symmetrical and cooperative working edges on the pick and chute, the pick having a pair of spaced nail receiving notches in its working edge and the chute having a corresponding pair of nail passage slots therein open to the working edge on opposite sides of the nail run, the notches being adapted upon oscillation of the pick to alternately register with the nail run and to receive a nail therefrom, and to then transfer said nail to and discharge the same through the corresponding nail passage slot, and means to oscillate the pick; the upper face of the pick at said notches being inclined downwardly and outwardly in the direction of the chute.

8. A nail feeding device comprising, with an inclined chute having a nail run therein open at its lower end, a supporting member mounted adjacent the lower end of the nail run, a rotary pick journaled on the member for oscillation about an upstanding axis, symmetrical and cooperative working edges on the pick and chute, the pick having a pair of spaced nail receiving notches in its working edge and the chute having a corresponding pair of nail passage slots therein open to the working edge on opposite

sides of the nail run, the relative spacing of the notches and passages being such that upon actuation of the pick through an oscillatory path of one extent the notches alternately register with the nail run and corresponding passage, and with actuation of the pick through an oscillatory path of lesser extent only one notch alternately registers with the nail run and corresponding passage, and means adapted to selectively receive devices adapted to intermittently cause oscillation of the pick through either path.

9. A nail feeding device comprising, with an inclined chute having a nail run therein open at its lower end, a supporting member mounted adjacent the lower end of the nail run, a rotary pick journaled on the member for oscillation about an upstanding axis, symmetrical and cooperative working edges on the pick and chute, the pick having a pair of spaced nail receiving notches in its working edge and the chute having a corresponding pair of nail passage slots therein open to its working edge on opposite sides of the nail run, the relative spacing of the notches and passages being such that upon actuation of the pick through an oscillatory path of one extent the notches alternately register with the nail run and corresponding passage, and with actuation of the pick through an oscillatory path of lesser extent only one notch alternately registers with the nail run and corresponding passage, a driven shaft, a cam arm on the pick overhanging the periphery of the shaft, and selectively interchangeable elements adapted to be received on the shaft for engagement with the cam arm, one such element being effective to throw the cam arm to carry the pick through one path and the other element being effective to throw the cam arm to carry the pick through the other path.

10. A nail feeding device comprising, with an inclined chute having a nail run therein open at its lower end, a supporting member mounted adjacent the lower end of the nail run, a rotary pick journaled on the member for oscillation about an upstanding axis, symmetrical and cooperative working edges on the pick and chute, the pick having a pair of spaced nail receiving notches in its working edge and the chute having a corresponding pair of nail passage slots therein open to the working edge on opposite sides of the nail run, the notches being adapted upon oscillation of the pick to alternately register with the nail run and to receive a nail therefrom, and to then transfer said nail to and discharge the same through the corresponding nail passage slot, and means to oscillate the pick; said last named means including a cross shaft adjacent the pick, the latter having a cam arm overhanging the shaft, an element on the shaft adapted to recurrently engage and swing the cam arm in one direction to impart half-oscillation to the pick in a corresponding direction, and a spring acting on the pick alternately with said element to impart half-oscillation thereto in the opposite direction to return it to starting position.

11. A nail feeding device comprising, with an inclined chute having a nail run therein open at its lower end, a supporting member mounted adjacent the lower end of the nail run, a rotary pick journaled on the member for oscillation about an upstanding axis, symmetrical and cooperative working edges on the pick and chute, the pick having a pair of spaced nail receiving notches in its working edge and the chute having a corresponding pair of nail passage slots

therein open to the working edge on opposite sides of the nail run, the notches being adapted upon oscillation of the pick to alternately register with the nail run and to receive a nail therefrom, and to then transfer said nail to and discharge the same through the corresponding nail passage slot, and means to oscillate the pick; said last named means including a cross shaft adjacent the pick, the latter having a cam arm overhanging the shaft, an element on the shaft adapted to recurrently engage and swing the cam arm in one direction to impart half-oscillation to the pick in a corresponding direction, and a spring acting on the pick alternately with said element to impart half-oscillation thereto in the opposite direction to return it to starting position, there being mechanism to rotate said shaft in a manner to cause a dwell between the action of said element and the spring, one of the notches then being in register with the nail run.

12. A nail feeding device comprising, with an inclined chute having a nail run therein open at its lower end, a supporting member mounted adjacent the lower end of the nail run, a rotary pick, means journaling the rotary pick on the member for oscillation about an upstanding axis, symmetrical and cooperative working edges on the pick and chute, the pick having a nail receiving notch in its working edge and the chute having a nail passage slot therein open to its working edges, and means to oscillate the pick to alternately register the nail receiving slot with said nail run and said nail passage slot for transfer of a nail therebetween; said pick journaling means including a tapered stem mounting the pick for tilting in a vertical plane.

13. In combination with a nail chute having a nail run, a nail pick co-operating with the nail run to pick nails therefrom, means effective to normally hold the nail pick in register with the nail run, means to intermittently oscillate the pick and carry it out of register with the nail run, yieldable means normally confining the pick to such normal oscillating movement but effective to allow the pick to tilt vertically when such oscillating movement is restricted and to clear it of the oscillating means.

14. In combination with a nail chute having a nail run, a nail pick co-operating with the nail run to pick nails, said nail pick being journaled on a vertical axis, a driven shaft, a cam arm on the pick overhanging the shaft at a tangent to the periphery thereof, circumferentially spaced buttons on the shaft, the cam surface of the cam arm extending across the path of travel of the buttons with rotation of the shaft and facing contra to the direction of travel of said buttons, and yieldable means effective to normally hold the cam arm in the path of travel of the buttons but allowing it to tilt upwardly upon any restriction of the movement of the button along the cam surface.
